UNITED STATES PATENT OFFICE.

GEORGE I. BAIR, OF DETROIT, MICHIGAN.

BOW-REST FOR VEHICLES.

1,254,762.

Specification of Letters Patent. Patented Jan. 29, 1918.

Application filed February 10, 1917. Serial No. 147,808.

To all whom it may concern:

Be it known that I, GEORGE I. BAIR, a citizen of the United States of America, residing at Detroit, in the county of Wayne and State of Michigan, have invented certain new and useful Improvements in Bow-Rests for Vehicles, of which the following is a specification, reference being had therein to the accompanying drawings.

10 This invention relates to bow rests and has special reference to the top holding devices used in connection with automobiles and vehicle bodies for holding the bows of a foldable top.

15 The primary object of my invention is to provide a bow rest having novel articulated members adapted for safely holding the superposed bows of a folded top, without injury to the bows or fabric in proximity thereto, and at the same time permit of a quick relief or get-away of bows or sockets thereof, when the members are swung to an open position and the top has to be raised.

20 Another object of my invention is to provide a bow rest wherein an arm and closure member are movably held relative to a stationary support with the arm and member articulated so that actuation of the member releases the arm, and permits of both parts assuming a position which provides clearance for bows in order that the top may be raised.

25 A further object of my invention is to furnish a bow rest with a novel closure member that may be easily and quickly actuated, particularly to a closed position, to coöperate with the arm and bow rest in embracing the uppermost bow or bow socket of a top, and thereby maintaining the other bows in position on the rest.

30 A still further object of my invention is to provide a bow rest wherein the parts are constructed with a view of facilitating manufacture, and at the same time retain those features by which durability, anti-rattling, and ease of manipulation and assembling are secured. With such ends in view, my invention resides in the novel construction to be hereinafter specifically described and then 35 claimed.

Reference will now be had to the drawings, wherein—

Figure 1 is a vertical sectional view of the bow rest in a closed position;

Fig. 2 is a side elevation of the same on a 55 smaller scale;

Fig. 3 is a plan of the bow rest on the same scale as Fig. 1;

Fig. 4 is a cross sectional view taken on the line IV—IV of Fig. 1; 60

Fig. 5 is a vertical sectional view of the bow rest in an open position;

Fig. 6 is a front elevation of the upper portion of the bow rest;

Fig. 7 is a similar view of the lower portion thereof, or a continuation of Fig. 6; and 65

Fig. 8 is a cross sectional view of the rest illustrating a slight modification.

In the drawings, 1 denotes a hollow arm having a foot portion 2, said arm and its 70 foot portion being somewhat L shaped in side elevation. The inner wall of the arm is provided with a rib 3 and the face of this rib is compound curved or provided with a central concavity and end convexities. Suitably mounted on the rib and conforming to the contour of the face thereof is a cushion member 4, preferably made of durable rubber, although any yieldable material that will withstand the elements may be used. This 80 cushioning member has its outer and inner faces of the same contour as the rib 3, so as to provide a central concave portion 5 and end convex portions 6, the latter adapted for separating top and bottom bows from intermediate bows of a folded top. The cushion member 4 may be suitably connected to the arm 1 and as illustrating the fastening means for said cushion member, rivets 7 are shown as extending through lugs 8 of the cushioning member that are disposed in recesses provided therefor in the convex portions of the rib 3. 85

The foot portion 2 of the arm 1 is recessed, as at 9, and provided with an angularly disposed slot 10, and terminates in a toe portion 11 having a groove or seat 12. The cushion member 4 extends on to the foot portion 2 of the arm 1 and embracing the foot portion 2 of said arm are the side and bottom walls 13 of a socket member or stationary support 14. The socket member 14 has the usual socket 15 and set screw 16 so that it may be mounted upon a body iron 17. The side walls 13 of the socket member 14 100 are connected by a transverse pin 18 extending through the angularly disposed slot 10 of the foot 2 and the slot 10 permits of the 105

arm and foot having a tilting action relative to the socket member 14, which is stationary. To assist in holding the arm and foot in a closed position, as shown in Fig. 1, the 5 socket member 14 has a rib 19 adapted to engage in the groove or seat 12, and thus maintain the foot 2 seated upon the pin 18 and the arm 1 substantially vertical or at right angles to the plane of the socket member 14. 10 The upper end of the arm 1 has the outer wall thereof cut away, as at 20 and the remaining walls terminating in a curved extension 21 at the inner side of the arm and onto which the cushion member 4 is extended. 15 The extension 21 has the extremity thereof provided with a recess or seat 22 and transversely of the extension is a pin 23. The ends of the pin 23 project into links 24 fixed relative to a curved closure member 25, 20 said member having a lining or cushioning member 26. The inner end of the member 25 is shaped to abut the end of the extension 21 and is provided with a rib 27 to engage in the groove or seat 22 of said extension. 25 The closing movement of the member 25 is limited by the extension 21 and when closed, said member has a fixed relation to the upper end of the arm, so as to coöperate with said arm in embracing and 30 holding the upper bow of a folded top.

The side walls of the arm 1, at the upper end thereof, are provided with a transverse pin 28 and pivoted on this pin is the crank portion 29 and side arms 30 of a channel lever 31. The side arms 30 have the ends thereof bifurcated or slotted, as at 32 to receive the links 24, said links being pivotally connected to the arms 30 by pins 33. The central crank portion 29 of the lever 31 is 35 pivotally connected by a pin 34 to the slotted or bifurcated head of the rod 35, said rod extending through the hollow arm 1 into the recess 9 of the foot 2. The lower end of the rod 35 is loosely connected, as at 40 36, to one end of the crank 37, fulcrumed in the recess 9 on a transverse pin or bearing 38. The opposite end of the crank 37 is pivotally connected by a pin 39 to the socket member 14 and it is through the medium of this connection and the pin and slot connection that the arm 1 and the foot thereof 45 may be adjusted relative to the socket member 14.

The outer wall of the arm 1 has a rotatable winged thumb screw 40 and one of the wings of said thumb screw is adapted to engage in a recess or seat 41 provided therefor in the end of the lever 31, so as to retain said lever in a closed position and yet permit of it being quickly released when it is desired to open the bow rest.

Assuming that the bow rest is closed, as shown in Fig. 1, and that the screw 40 is turned to release the lever 31, said lever can 55 be raised and its movement is facilitated by

the weight of the bow upon the foot of the arm 1, as the foot projects above the side walls 13 of the socket member 14. As the lever 31 is raised, the rod 35 connected to the crank 37 is lowered with the pin 39 serving as a pivot to laterally shift the foot 2 and move the toe out of engagement with the rib 19 of the socket member. When the foot is released in this manner, the arm 1 can swing upwardly relative to the socket member and assume the angular relation shown in Fig. 5. Simultaneous with this operation the links 30 are shifted on the ends of the pins 23 to open the closure member 25, thus liberating all bows previously held by the rest.

I attach considerable importance to the fact that the arm 1 swings outwardly relative to the socket member 14, as this arrangement permits of the rest being advantageously used in connection with automobiles provided with "gypsy curtains" and "Victoria" tops. Such tops cannot be held by ordinary bow rests, for instance of the well known "Bair" type. These rests have 90 back pieces that prohibit their use in connection with "gypsy curtains" and "Victoria" tops, whereas my improved bow rest simply engages the outer sides of the bows and will provide clearance for any fabric 95 between the bows and the body of the automobile.

Furthermore, the arms of a set of rests positively prevent lateral or sidewise movement of the folded top, and it is unnecessary to use straps or like devices after the top is folded.

One embodiment of my invention has been illustrated, but it is to be understood that the structural elements are susceptible to 105 such changes in size, shape and manner of assemblage as fall within the scope of the appended claims.

What I claim is:—

1. A bow rest comprising a socket member, an arm carried thereby and adapted to be swung outwardly, a pivoted closure member carried by the upper end of said arm, and means carried by said arm and connected to said closure member adapted for holding said arm rigid relative to said socket member and said closure member in a closed position.

2. A bow rest comprising a socket member, a movable arm carried thereby, a pivoted closure member carried by said arm, means carried by said arm for simultaneously fixing said arm relative to said socket member and said closure member relative to said arm.

3. A bow rest comprising a socket member, an arm carried thereby and having a foot portion for engagement with said socket member to maintain said arm rigid relative thereto, and means carried by said arm and

connected to said socket member and adapted for shifting said arm to release the toe portion thereof relative to said socket member.

5. 4. A bow rest comprising a socket member, an arm movable relative thereto and having a toe portion adapted for engagement with said socket member to maintain said arm rigid relative thereto, a movable closure member at the upper end of said arm, and means carried by said arm adapted for simultaneously shifting said closure member and releasing the toe portion of said arm relative to said socket member.

15. 5. A bow rest comprising a socket member, an arm supported by said socket member and having the toe portion adapted for engagement therewith to maintain said arm rigid relative to said socket member, a pivoted closure member carried by the upper end of said arm, and means including a rod within said arm and a lever at the upper end of said arm for simultaneously moving said closure member and releasing the toe portion of said arm relative to said socket member.

6. A bow rest comprising a socket member having a rib, an arm loosely connected to said socket member adapted to engage superposed bows and having a toe portion adapted to engage the rib of said socket member to maintain said arm rigid relatively thereto, means at the upper end of said arm adapted to engage the uppermost bow, and means coöperating with said upper bow engaging means and with said toe and rib in maintaining said arm rigid.

7. A bow rest comprising a socket member, a hollow arm loosely connected thereto and having a toe portion adapted to engage in said socket member to maintain said arm in a vertical position relative to said socket member, a closure member at the upper end of said arm, and means articulating said closure member and said socket member so

that said closure member and said arm may be simultaneously moved relative to said socket member.

8. A bow rest comprising a socket member, a hollow arm loosely supported thereby and having a toe portion adapted to engage in said socket member to maintain said arm vertical relative thereto, a closure member carried by the upper end of said arm, and means extending through said arm and articulating said closure member and said socket member so that said closure member may be shifted relatively to said arm and said arm shifted relatively to said socket member.

9. A bow rest comprising a socket member, a hollow arm loosely connected thereto and having a toe portion extending into said socket member and adapted to maintain said arm rigid relative thereto, a pivoted closure member carried by the upper end of said arm, a lever connected to said arm, and adapted for moving said closure member relative to said arm, and means extending through said arm and articulating said lever relative to said socket member so that said arm may be shifted relative to said socket member.

10. In a bow rest, an arm, a pivoted closure member carried by the upper end thereof, a lever carried by said arm and connected to said member and adapted for shifting said member relative to said arm, means in said arm connected to said lever for effecting an outward movement of the lower end of said arm when said lever is pulled outwardly, and means adapted for supporting said arm so that said arm may be swung outwardly relative to its supporting means.

In testimony whereof I affix my signature in the presence of two witnesses.

GEORGE I. BAIR.
